(57) **CLAIM**

The ornamental design for a car modified front lip, as shown and described.

DESCRIPTION

FIG. 1 is a perspective view of the car modified front lip showing my new design;

FIG. 2 is another perspective view of the car modified front lip showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 in FIG. 3; and,

FIG. 10 is a partial enlarged view of portion 10 in FIG. 7.

Broken lines used in the drawings represent portions of the car modified front lip that form no part of the claimed design.
